UNITED STATES PATENT OFFICE

2,247,390

THREAD TREATING APPARATUS

Walter F. Knebusch, Rocky River, and Alden H. Burkholder, Cleveland, Ohio, assignors to Industrial Rayon Corporation, Cleveland, Ohio, a corporation of Delaware

Original application February 1, 1936, Serial No. 61,956. Divided and this application February 2, 1939, Serial No. 254,244

6 Claims. (Cl. 34—122)

This invention relates to apparatus for the continuous treatment of filaments, thread, ribbons, bands, tapes or like materials, hereinafter referred to as "thread."

More particularly, the invention relates to apparatus comprising a housing substantially completely enclosing a device for continuously but temporarily storing thread being subjected to a processing operation such, for example, as drying. The invention provides a thread-advancing thread store device of cantilever form; e. g., a thread-advancing reel, which advances the thread toward the unsupported end thereof in a plurality of closely spaced, generally helical turns, together with a chamber including a closure adapted to expose the interior of the chamber to provide access to the thread-advancing thread store device. The invention thus provides a particularly efficient apparatus for conserving the treating medium without sacrificing accessibility to the thread-storage, thread-advancing device enclosed in the chamber.

By way of illustration, but in no sense of limitation, the invention will be described in connection with the continuous processing of artificial silk thread on apparatus of a type generally similar to that shown, described and claimed in a prior application for patent entitled "Manufacture of artificial silk" Serial No. 7,114, filed February 18, 1935, by Walter F. Knebusch and Alden H. Burkholder. In the present application, as in said prior application, the apparatus shown comprises a plurality of thread-advancing thread store devices disposed in processing sequence. Liquid processing treatments are applied to the thread on certain of the earlier thread-advancing thread store devices, after which the thread is continuously dried by apparatus embodying the present invention.

This application is a division of copending application Serial No. 61,956, filed February 1, 1936.

In the drawings, Figure 1 is a sectional elevation from line 1—1 of Figure 2 of a portion of an apparatus for the continuous processing of thread, such apparatus embodying the features of the present invention. Figure 2 is a front elevation of a portion of said continuous processing apparatus. Figure 3 is a sectional elevation of a portion of such apparatus showing on an enlarged scale one embodiment of the invention as employed in the drying of thread, the section being taken along lines 3—3 of Figures 2 and 5. Figure 4 is a plan on the same scale of the apparatus of Figure 3, showing in broken lines the closure as it appears when the chamber is opened.

Figure 5 is a front elevation of the apparatus of Figures 3 and 4, part of the closure being broken away to show the thread-advancing thread store device.

5 In the apparatus illustrated in Figures 1 and 2, thread A from a suitable source, such as a preceding thread-advancing thread store device, proceeds in sequence to each of a series of thread-advancing thread store devices 1, 2, 3 and 4. The 10 thread-advancing thread store devices shown are of cantilever form; i. e., supported and driven from one end only, each serving to advance the thread toward the unsupported end thereof in a large number of closely spaced, generally helical turns. They are preferably disposed in stepped arrangement with the discharge end of each device in apposition to the receiving end of the succeeding device. Thread-advancing thread store devices 1, 2 and the preceding devices may 15 be devoted to the wet processing of the thread, while thread-advancing thread store device 3 may constitute a drip stage. Thread-advancing thread store device 4 forming part of so much of the apparatus as embodies the present invention, is devoted to drying of the thread.

20 As shown in Figure 2, the apparatus as a whole comprises a plurality of adjacent descending series of thread-advancing thread store devices each of which series handles a single thread.

25 30 The thread-advancing thread store devices may, if desired, operate on the principle of the thread-advancing reel illustrated in Figures 3 and 5. Such reel comprises two rigid, generally cylindrical members 6 and 7 the peripheries of which are respectively made up of bar members 9 and 10. Member 6, which may be termed the concentric member, is mounted concentrically upon and for rotation with drive shaft 8. Member 7, which may be termed the eccentric member, is rotatably mounted with its axis slightly offset from and inclined to that of the concentric member 6. Bar members 10 of concentric member 7, which bar members are disposed alternately with bar members 9 of concentric member 6, are reinforced at their outer ends by annular member 14.

35 40 45 50 55 Eccentric member 7 constitutes part of a generally cylindrical cake-like member 11 mounted, as by bolts 13, on annular supporting member 12. Annular supporting member 12 is rotatably supported in offset and inclined relation, preferably in the skew relation shown, to the axis of concentric member 6. To that end, annular supporting member 12 is mounted on frame member 15, the shaft 8 being journaled in or otherwise supported in the desired relationship to frame

member 15. A bushing 16 may, if desired, be provided in annular supporting member 12 to act as a bearing.

The reel of Figures 3 and 5 is particularly adapted to the application to the thread stored on the reel of a processing medium; e. g., a drying fluid, from the interior of the reel. In the embodiment of the invention, illustrated in the drawings, the means for accomplishing this function comprises a hollow drive shaft 8 communicating through ports 17 with a chamber 18 in the body portion of concentric member 6. A plurality of holes 19, which may conveniently be spaced between the bar members 9 of concentric member 6, provide communication between the chamber 18 and the periphery of the reel. Plug bolt 20, which is shown as closing the end of hollow shaft 8, also holds concentric member 6 against the pin 21 in shaft 8. Pin 21 serves to locate member 6 longitudinally of the shaft and also drives member 6, since the projecting ends of pin 21 are positioned in a slot 22 in member 6.

Sealing means 23 may be provided, if desired, to prevent the escape of the processing or drying medium past shaft 8. To prevent the entrance of extraneous substances into that portion of the reel mechanism at the junction of concentric member 6 and eccentric member 7 and to prevent the escape of lubricants which might contaminate the thread on the reel, sealing means 24 are provided. Sealing means 24 preferably take the form of a flexible sleeve of bellows construction, the latter type of construction being desirable in view of the occurrence of a limited relative movement between the parts on which such sleeve seats.

Rotation of the drive shaft 8 results in rotation of concentric member 6, which is rigidly fixed thereto. Contact of bar members 9 of concentric member 6 with bar members 10 of eccentric member 7 causes said eccentric member to rotate at the same angular speed. During such rotation, the offset relationship of the generally cylindrical members 6 and 7 causes the thread to transfer from the bar members of one generally cylindrical member to the bar members of the other generally cylindrical member. At the same time, the inclined relationship of said generally cylindrical members causes the thread to advance in a plurality of spaced, generally helical turns to the unsupported end. Reels of the type illustrated in this application are shown, described and claimed in copending application Serial No. 61,954, filed February 1, 1936.

In the illustrated apparatus, processing liquid is showered down on the thread stored on each of reels 1 and 2, as well as on certain of the reels prior thereto, from suitably positioned reagent distributors 33 supplied by pipes 34 extending longitudinally of the apparatus and serving all corresponding reels in the same horizontal series. The processing liquid is collected in troughs 35 of suitable design likewise extending longitudinally of the apparatus and serving corresponding reels in the same horizontal series. The liquid so collected may be passed to the sewer, particularly if it is one which cannot to advantage be re-used, or, if desired, recirculated by suitable means through pipe 34.

As previously mentioned, it is desirable in continuous processing apparatus to provide a drip stage after the last of the liquid processing stages. Thus in the apparatus shown in Figures 1 and 2, the last of the various processing liquids to be applied; i. e., wash water, may be showered

onto the thread on reel 2, in which case reel 3 may constitute a drip stage; that is to say, a stage in which no processing liquid is applied to the thread but on which the liquid carried over from the preceding stage is allowed to drip off into the collecting trough 35. A very substantial portion of the excess moisture may be removed in this manner before the thread is subjected to the drying operation on reel 4. A large saving can thus be effected in the amount of drying medium used and a less intense drying treatment is necessary, since much less moisture remains to be removed from the thread.

In the apparatus of Figures 1 and 2, the thread is dried on a reel of the type shown in Figures 3 and 5. Drying medium is applied to the thread from the interior of the reel through the hollow drive shaft 8. To aid in the drying of the thread by intensifying the use of the drying medium, to reduce the amount of drying medium required, and to permit more accurate control of drying conditions in the immediate vicinity of the reel, it has been found desirable to enclose each drying reel 4 in a chamber 36. As shown, chamber 36 substantially completely encloses reel 4, thus minimizing the escape of the drying medium.

In the illustrated embodiment of the invention, the chamber 36 for each reel 4 comprises a movable closure 40 made up of the front wall and a portion of the top wall and a cooperating stationary portion made up of a portion of the top wall, the back wall, side walls, and the bottom wall. The movable closure includes the front wall 37 mounted by means of hinges 48 on one of the side walls 38 of the chamber and the integrally formed portion 39 of the top wall 41 of the chamber. As shown, portion 39 of the top wall 41 cooperates with a stationary portion 43 forming the remainder of the top wall 41 of the chamber; i. e., the portion of the top wall associated with the stationary portion of the chamber. The movable portion 39 of the top wall 41 of the chamber extends over substantially the entire thread-bearing periphery of the reel.

When closure 40 is swung open on hinges 48, as shown in broken lines in Figure 4, the entire unsupported end of the reel and the entire upper portion of the thread-bearing portion of the reel are accessible for operating purposes.

A slot 42 in the top wall 41 of the chamber 36, through which the thread passes when entering the chamber, is provided at the juncture of the movable portion 39 of the top wall 41 and the stationary portion 43 thereof. If the slot 42 is formed in the movable portion 39, it may be formed as shown in Figure 4 to prevent interference with the thread when the front wall 37 and portion 39 of the top wall 41 are swung open to provide access to the reel. A similar slot 44 is provided in bottom wall 45 of the chamber 36 through which slot 44 the thread may leave the chamber. As shown in the illustrated embodiment of the invention, the slot 44 in the bottom wall 45 of the chamber may be partially or substantially closed by an extending member 46 carried by front wall 37 to a position under a portion of bottom wall 45.

When access is desired to the reel 4 in the chamber 36, latch 47 is operated, after which the front wall 37 together with the top portion 39 and extending member 46 are swung back on the hinges 48, exposing the front, top and a portion of the sides of the reel. Threading up of the reel thereafter becomes a very simple matter. The thread A is led onto the reel at the rear, is caused

to progress along the reel during rotation thereof, and is led off the reel at the front thereof through the slot 44 in the bottom wall 45 of the chamber. The chamber may then be closed, the slot 42 eliminating any interference between the portion 39 and the thread proceeding to the reel.

As is apparent from Figures 2, 4 and 5, each pair of immediately adjacent chambers 36 has a common side wall 38, while a plurality of adjacent chambers have other walls in common, as bottom, top, and back walls which extend longitudinally of the apparatus as a whole.

If desired, the processing medium supplied to each chamber 36 may be recirculated as shown in the apparatus of Figures 1 and 2. In such apparatus, the drying medium, such, for example, as heated air, supplied to each chamber 36 from the interior of the reel is exhausted from such chamber 36 through duct 49 which communicates with the exhaust conduit 50 extending longitudinally of the machine as a whole. The spent drying medium then passes through reconditioning apparatus 51, after which it passes to the supply conduit 52 likewise extending longitudinally of the apparatus as a whole. From the latter, as by means of ducts 53, the drying medium is supplied to the chambers 36 from the interiors of the reels 4 through hollow drive shafts 8. Air or other inert gas, which may or may not be heated, may be employed as the drying medium. A humidifying medium may be used without departing from the spirit of the invention.

A cap twister 5, which serves as the means for collecting the thread A after it leaves the last reel 4, may be advantageously employed, if desired.

In the arrangement shown, a plurality of bobbins are mounted on a lifting rail 66 which is supported by the brackets 67. Brackets 67 are designed to guide the lifting rail, each comprising guide surfaces 68 which slide on a rigidly supported guide rod 69. The lifting rail 66 is reciprocated vertically by flexible members such as chains 71 fastened at one end to the lifting rail and at the other end to the sprockets 72 rigidly mounted on a rotatable shaft 73 extending parallel to the lifting rail. The shaft 73 is so actuated as to cause the chains 71 to wind on and unwind from sprockets 72, thus reciprocating lifting rail 66. The necessary motion is imparted to shaft 73 by flexible members 74 adapted to wind on and unwind from sprockets 75 rigidly mounted on shaft 73 and actuated by lever 76 from cam 77 mounted on drive shaft 78. Counterweights 80 may be employed to counterbalance the weight of the reciprocating parts.

The bobbin-supporting whorls 79 of each pair of adjacent bobbins are driven by belt 82 from a rapidly rotating drum 83. Guide rollers 84, adapted to reciprocate vertically by being supported by brackets 67, may be provided to guide the belts 82 to the whorls 79. A belt tightener 85 may also be supplied for each belt. To prevent the "balloons" formed by the threads during the operation of each twister from interfering with those of adjacent twisters, shields 86 may be provided between twisters. Such shields may conveniently be connected to and made part of the supporting means of the chamber 36 and may also support the thread guides 87 through which the thread passes on its way to the cap twisters 5.

In the apparatus shown, the thread has an approximately straight travel from the drying

reel 4 to the bobbin. Consequently, the actual twisting of the thread takes place at least as far back as the point at which the thread is discharged from the reel and perhaps even on the reel itself within a short distance of the point at which the thread leaves the reel. In either case, the twist is introduced into the thread in the chamber 36; accordingly, the thread is twisted while being subjected to the processing conditions obtained in such chamber.

Obviously, treatments other than those herein disclosed may be carried out in connection with the apparatus of the invention. The apparatus itself may be modified in various ways to suit the purpose for which it is to be used without, however, departing from the inventive concept. The improvements herein described may readily be incorporated in apparatus differing materially from that illustrated. The features of the invention may also be applied to treatments other than those employed in the processing of artificial silk thread.

It is intended that the patent shall cover, by suitable expression in the appended claims, whatever features of patentable novelty reside in the invention.

What is claimed is:

1. Apparatus for treating thread comprising a cantilever thread-advancing thread store device which advances the thread lengthwise thereof in a plurality of spaced generally helical turns; a multi-sided enclosure confining said device, including a housing having an opening exposing the unsupported end of the thread-advancing thread store device and a part of the thread-bearing periphery extending substantially the entire length of said thread-advancing thread store device, a pivotally mounted movable closure cooperating, when in the closed position, with said housing to enclose said thread-advancing thread store device substantially entirely, a slot disposed at the juncture of said closure and said housing apposite one end of said thread-advancing thread store device through which slot the thread passes to said thread-advancing thread store device from a point outside said enclosure, and another slot through which the thread passes from said thread-advancing thread store device disposed at the juncture of said closure and said housing apposite the other end of said thread-advancing thread store device; means whereby an inert gas is admitted to said housing; and means associated with said housing whereby said inert gas is removed from said housing.

2. Apparatus for treating thread comprising a cantilever thread-advancing thread store device which advances the thread lengthwise thereof in a plurality of spaced generally helical turns; a multi-sided enclosure confining said device including a housing having an opening exposing the unsupported end of the thread-advancing thread store device and a part of the thread-bearing periphery extending substantially the entire length of said thread-advancing thread store device; a pivotally mounted movable closure forming at least two sides of the enclosure cooperating with said housing to enclose said thread store device substantially entirely, a slot through which the thread passes to said thread store device being disposed at the juncture of said closure and said housing; means whereby an inert gas is admitted to said housing; and means associated with said housing whereby said inert gas is removed from said housing.

3. Apparatus for treating thread comprising a cantilever thread-advancing thread store device which advances the thread lengthwise thereof in a plurality of spaced generally helical turns; a multi-sided enclosure confining said device including a housing having an opening exposing the unsupported end of the thread-advancing thread store device and a part of the thread-bearing periphery extending substantially the entire length of said thread-advancing thread store device; a pivotally mounted movable closure cooperating, when in the closed position, with said housing to enclose said thread-advancing thread store device substantially entirely, a slot through which the thread passes to said thread-advancing thread store device being disposed at the juncture of said closure and said housing apposite one end of said thread-advancing thread store device and another slot through which the thread passes from said thread-advancing thread store device being disposed at the juncture of said closure and said housing apposite the other end of said thread-advancing thread store device; and means for heating said thread-advancing thread store device.

4. Apparatus for treating thread comprising a cantilever thread-advancing thread store device which advances the thread lengthwise thereof in a plurality of spaced generally helical turns; a housing and a pivotally mounted movable closure therefor defining a polyhedron of at least six sides substantially entirely enclosing said thread-advancing thread store device, said closure comprising the face of the polyhedron adjacent the unsupported end of said thread-advancing thread store device and a substantial portion of at least one adjacent face of said polyhedron, whereby when said closure is opened the unsupported end of said thread-advancing thread store device and a part of the thread-bearing periphery extending substantially the entire length of said thread-advancing thread store device is exposed; means whereby an inert gas is admitted to said housing; and means associated with said housing whereby said inert gas is removed from said housing.

5. Apparatus for treating thread comprising a cantilever thread-advancing thread store device which advances the thread lengthwise thereof in a plurality of spaced generally helical turns; a housing and a pivotally mounted movable closure therefor defining a polyhedron of at least six

sides substantially entirely enclosing said thread-advancing thread store device, said closure comprising the face of the polyhedron adjacent the unsupported end of said thread-advancing thread store device and a substantial portion of at least one adjacent face of said polyhedron, whereby when said closure is opened the unsupported end of said thread-advancing thread store device and a part of the thread-bearing periphery extending substantially the entire length of said thread-advancing thread store device is exposed; a slot through which the thread passes to said thread store device from a point outside said housing, said slot being disposed at the juncture of said closure and said housing; means whereby an inert gas is admitted to said housing; and means associated with said thread-advancing housing whereby said inert gas is removed from said housing.

6. Apparatus for treating thread comprising a cantilever thread-advancing thread store device which advances the thread lengthwise thereof in a plurality of spaced generally helical turns; a housing and a pivotally mounted movable closure therefor defining a polyhedron of at least six sides substantially entirely enclosing said thread-advancing thread store device, said closure comprising the face of the polyhedron adjacent the unsupported end of said thread-advancing thread store device and a substantial portion of at least one adjacent face of said polyhedron, whereby when said closure is opened the unsupported end of said thread-advancing thread store device and a part of the thread-bearing periphery extending substantially the entire length of said thread-advancing thread store device is exposed; a slot through which said thread passes to said thread-advancing thread store device from a point outside said housing, said slot being disposed at the juncture of said closure and said housing apposite one end of said thread-advancing thread store device; a second slot through which the thread passes from said thread-advancing thread store device to a point outside said housing, said second slot being disposed at the juncture of said closure and said housing apposite the other end of said thread-advancing thread store device; and means for heating said thread-advancing thread store device.
